CLAIM

The ornamental design for a toy, as shown and described.

DESCRIPTION

FIG. 1 is a front perspective view of a toy, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of the toy shown in a state of use.

The broken lines in FIGS. 1-8 illustrate portions of the toy that form no part of the claimed design. The additional broken lines in FIG. 9 illustrate environmental structure that forms no part of the claimed design.

1 Claim, 9 Drawing Sheets
